US00D915211S

(12) **United States Design Patent** (10) Patent No.: **US D915,211 S**
Green et al. (45) Date of Patent: ** Apr. 6, 2021

(54) **CLEANING PRODUCT DISPENSER**

(71) Applicant: **Kimberly-Clark Worldwide, Inc.**, Neenah, WI (US)

(72) Inventors: **Jonathan Green**, Rossett (GB); **Joseph Oberdorf**, Leiden (NL)

(73) Assignee: **KIMBERLY-CLARK WORLDWIDE, INC.**, Neenah, WI (US)

(**) Term: **15 Years**

(21) Appl. No.: **29/700,782**

(22) Filed: **Aug. 6, 2019**

(51) LOC (13) Cl. **09-01**

(52) U.S. Cl.

USPC **D9/531**; D6/523; D7/536

(57) **CLAIM**

The ornamental design for a cleaning product dispenser, as shown and described.

DESCRIPTION

FIG. 1 is a perspective view showing our new design for a cleaning product dispenser;
FIG. 2 is a front view of the embodiment of FIG. 1;
FIG. 3 is a back view of the embodiment of FIG. 1;
FIG. 4 is a left side view of the embodiment of FIG. 1, with the right side view being a mirror image of FIG. 4;
FIG. 5 is a top view of the embodiment of FIG. 1;
FIG. 6 is a bottom view of the embodiment of FIG. 1;
FIG. 7 is a perspective view showing an alternate design for a cleaning product dispenser;
FIG. 8 is a front view of the embodiment of FIG. 7;
FIG. 9 is a back view of the embodiment of FIG. 7;
FIG. 10 is a left side view of the embodiment of FIG. 7, with the right side view being a mirror image of FIG. 10;
FIG. 11 is a top view of the embodiment of FIG. 7; and,
FIG. 12 is a bottom view of the embodiment of FIG. 7.
The claim is limited to the elements shown in solid lines. In the figures, the broken lines represent unclaimed subject matter and form no part of the claim.

1 Claim, 12 Drawing Sheets
